(57) **CLAIM**

The ornamental design for an adjustable shelf unit as shown and described.

DESCRIPTION

FIG. 1 is a top-right perspective view of the adjustable shelf unit of the present invention;

FIG. 2 is a front elevation view of the adjustable shelf unit shown in FIG. 1;

FIG. 3 is a rear elevation view of the adjustable shelf unit shown in FIG. 1;

FIG. 4 is a left side elevation view of the adjustable shelf unit shown in FIG. 1;

FIG. 5 is a right side elevation view of the adjustable shelf unit shown in FIG. 1;

FIG. 6 is a top plan view of the adjustable shelf unit shown in FIG. 1; and,

FIG. 7 is a bottom plan view of the adjustable shelf unit shown in FIG. 1.

The drawings illustrate an adjustable shelf unit, as shown in the drawings. Contour lines are included in the various views of FIGS. 1 through 7 to depict surface curvature, flatness and/or other shapes. Illustrative portions that are depicted in broken lines form no part of the claimed design.

1 Claim, 4 Drawing Sheets
